DISPENSER TOP FOR A PRESSURE CAN

Nels W. Seaquist, Crystal Lake, Ill., assignor, by mesne assignments, to Seaquist Valve Company, Division of Pittsburgh Railways Company, Cary, Ill., a corporation of Pennsylvania

Filed July 8, 1964, Ser. No. 80,750

Term of patent 3½ years

(Cl. D58—26)

FIG. 2

FIG. 1

FIG. 3

FIG. 4

FIG. 1 is a top rear perspective view of a dispenser top for a pressure can, showing my new design;

FIG. 2 is a rear elevational view thereof;

FIG. 3 is a top plan view thereof; and

FIG. 4 is a front elevational view thereof.

The portions shown in broken lines are for illustrative purposes only.

I claim:

The ornamental design for a dispenser top for a pressure can, as shown and described.
